UNITED STATES PATENT OFFICE

WALTER E. LIPPERT, OF HEWLETT, NEW YORK, ASSIGNOR TO TECO MANUFACTURING CORP., OF NEW YORK, N. Y., A CORPORATION OF NEW YORK

DESIGN FOR AN ELECTRIC INSECTICIDE

Application filed July 30, 1932. Serial No. 44,492. Term of patent 3½ years.

To all whom it may concern:

Be it known that I, WALTER E. LIPPERT, a citizen of the United States, residing in Hewlett, county of Nassau, Long Island, State of New York, have invented a new, original, and ornamental Design for Electric Insecticide, of which the following is a specification, reference being had to the accompanying drawing, forming part thereof.

In the drawing:

Fig. 1 is a side elevation of the article showing my new design, and

Fig. 2 is a plan view of the same.

I claim:

The ornamental design for an electric insecticide, as shown.

WALTER E. LIPPERT.
